RADIO RECEIVING SYSTEM

Roy A. Weagant, Douglaston, Long Island, N. Y.,
assignor to Radio Corporation of America, a
corporation of Delaware

Application July 9, 1940, Serial No. 344,488

11 Claims. (Cl. 250—20)

My present invention relates to radio receiving systems, and more particularly to systems of the type using carrier exaltation networks in connection with phase detection.

In prior applications I have disclosed and claimed various networks constructed and arranged to detect the signal energy of a desired carrier frequency even though strong adjacent channel interference existed, or even though strong static disturbance impulses were being collected. Essentially, these earlier disclosed systems comprised phase detection circuits wherein the desired signal energy was impressed upon a detector network with highly amplified oscillations of substantially the signal carrier frequency.

One of the main objects of my present invention is to provide an improved type of receiving system which utilizes phase detection networks, and wherein there is utilized phase detection stages in cascade thereby greatly to improve the selectivity of the receiving system, as well as to increase the rejection of static disturbances.

Another important object of this invention is to provide a receiving system which utilizes a prior network constructed and arranged to derive from modulated signal carrier energy second harmonic energy, and a subsequent detection stage being employed to combine the modulated second harmonic energy with highly amplified second harmonic energy whose modulation frequency components have been substantially all removed.

Another object of this invention is to arrange in cascade a plurality of signal transmission stages, and in each of the stages combining the signal energy with highly amplified unmodulated voltage of a frequency which is substantially equal to the mid-band frequency of the signal energy applied to each of said stages.

Still another object of the invention is to improve greatly the selectivity of a receiving system, as well as greatly to reduce the effect of static disturbances on the latter, by converting received signal energy to an intermediate frequency, then combining the intermediate frequency energy with highly amplified voltage of the intermediate frequency carrier substantially free of modulation components thereby to produce signal energy of the second harmonic of the intermediate frequency carrier, and finally combining the second harmonic energy with unmodulated voltage of substantially the second harmonic frequency in a detection network.

And still other objects of the invention are to improve generally the efficiency and selectivity of

radio receiving systems, and to provide such systems in a reliable manner capable of economic construction and assembly.

The novel features which I believe to be characteristic of my invention are set forth in particularity in the appended claims; the invention itself, however, as to both its organization and method of operation will best be understood by reference to the following description taken in connection with the drawings in which I have indicated diagrammatically several circuit organizations whereby my invention may be carried into effect.

In the drawings:

15 Fig. 1 shows a receiving system which embodies the invention,

Fig. 2 illustrates a modification,

Fig. 3 shows still another modification.

Referring to Fig. 1, there is shown a superheterodyne type of receiver which may be of the type utilized in the standard broadcast receiving range of 550-1700 kilocycles (kc.). It is to be understood, however, that the invention is not restricted to this receiving range, but may be used with equal utility in the other well known frequency bands of radio communication. The signal collector device 1 is shown as of the grounded antenna type, but it may be a loop collector or radio frequency distribution line or even the type of signal collector device used on a mobile vehicle, such as an automobile. The collected signals are preferably directly impressed upon the tunable input circuit 2 of a converter network 3. The converter may be of the combined local oscillator-first detector type using a pentagrid tube, but it may also embody independent local oscillator and first detector tubes, if desired. The numeral 4 denotes a tunable oscillator tank circuit, and each of circuits 2 and 4 includes independent tuning devices such as variable condensers. The dotted line 5 designates the mechanical uni-control arranged to adjust the rotors of the variable tuning condensers of circuits 2 and 4. Of course, circuit 4 will be tuned over a local oscillation frequency range which is higher than that of the signal frequency range by the operating intermediate frequency (I. F.) value, and the I. F. value may be chosen from a range of 75 to 456 kc.

50 The resonant output circuit 6 of the converter is tuned to the I. F. value, and is coupled to the tuned input circuit 7 of the I. F. amplifier tube 8. The latter may be of the 6L7 type. This type of tube has five grids arranged between its cathode 9 and plate 10, and the first grid 11 may be connected to one side of the input circuit 7. The

mid-point of the coil of circuit 7 is established at ground potential with respect to alternating currents, and a direct current blocking condenser may be inserted in the ground connection. The cathode 8 is connected to ground through the usual self-biasing resistor 12 which is shunted for I. F. currents by an I. F. bypass condenser.

The third grid 13 is surrounded by a positive screening field, and the grid itself is connected to a source of highly amplified voltage of I. F. value. This source of voltage is a regenerative amplifier comprising tube 14 which has its output electrode 15 regeneratively coupled through condenser 16 to the control grid 11. The grid 17 is connected to the lower end of input circuit 7, while the grid 13 is connected through a direct current blocking condenser 18 to the high potential end of coil 19. The opposite end of coil 19 is connected to a source of positive potential, while condenser 20 arranged in shunt with coil 19 resonates the coil to the I. F. value. The grid leak resistor 21 connects grid 13 to ground thereby establishing the grid 13 at a direct current voltage which is negative with respect to cathode 9 by the voltage drop across resistor 12.

The cathode of tube 14 is connected to ground through the self-biasing resistor 22 which is shunted by the usual I. F. bypass condenser. The function of tube 14, and its associated circuits, is to feed to grid 13 voltage of the I. F. value which is substantially free of all modulation frequency components. That is, the regenerative amplifier tube 14 functions to exalt, or augment, the I. F. energy at carrier frequency, and by virtue of this sharp characteristic it substantially strips away all modulation components up to about two or three hundred cycles. Of course, even the latter components may be removed.

The plate 10 of tube 8 is connected to a source of positive potential through a coil 23 which is shunted by tuning condenser 24. The network 24-23 is tuned to the second harmonic of the I. F. carrier value. Hence, if the I. F. value is 450 kc., by way of illustration, then circuit 24-23 is tuned to 900 kc. It will be noted that there is impressed on the grids 11 and 13 of tube 8 voltages of the I. F. carrier value. The tube 8 functions in the manner of a mixer tube, and the voltages on grid 11 and 13 are applied in opposite phase. Hence, the rectified output voltage appearing across output circuit 24-23 will be proportional to the product of the accentuated, or exalted, I. F. carrier voltage delivered by tube 14 and the I. F. signal input delivered to grid 11. There are developed in the output circuit 24-23 of mixer tube 8 two products of rectification. These are audio frequencies and the second harmonic of the signal input frequencies.

The audio frequencies are excluded by virtue of the fact that the output circuit is tuned to the second harmonic of the I. F. carrier value. When modulation exists on the desired signal carrier there will exist in the output circuit 24-23 the usual modulation side bands of double frequency. It is highly desirable that the mixer tube 8 have a square law rectification characteristic for weak signals, and that the signal voltage of grid 11 be very small in proportion to the accentuated I. F. carrier voltage fed to grid 13. Attention is directed to the phenomenon of selective improvement in detector efficiency which occurs in such a case, as dis-

closed in my co-pending application Serial No. 335,892 filed May 18, 1940.

The second detector network comprises a diode 26 whose anode is connected by the condenser 27 to the high potential side of the input circuit 28. The input circuit 28 is magnetically coupled to the I. F. mixer output circuit 24-23, and is fixedly tuned to the second harmonic of the I. F. value. The cathode of diode 26 is connected to ground, and the diode load resistor is designated by the numeral 29. Resistor 29 is connected between the anode 26 of diode and ground, condenser 30 being connected in shunt with resistor 29 in order to by-pass all high frequency currents. The low potential side of input circuit 28 is connected to ground through a resonant circuit 31 which is tuned to the second harmonic of the I. F. There is injected into circuit 31 the highly amplified unmodulated voltage whose frequency is equal to the second harmonic of the I. F. This is accomplished by connecting the plate of tube 32 to its signal grid through the coupling condenser 33, and impressing upon the grid of tube 32 the second harmonic signal energy developed across circuit 24-23.

The condenser 34 connects the grid of tube 32 to the plate 10 of mixer tube 8. In the plate circuit of tube 32 there is included a resonant circuit 35 which is tuned to the second harmonic of the I. F., circuit 35 being magnetically coupled to circuit 31 so as to provide a sharply selective circuit. The cathode of tube 32 is connected to ground through a properly by-passed bias resistor 36. The tube 32 and its associated circuits provide a second regenerative amplifier which is similar in construction to the regenerative amplification circuit embodying tube 14. This second regenerative amplifier circuit functions to provide accentuated unmodulated voltage of a frequency equal to the second harmonic of the I. F.

Due to the relatively high selectivity of the regenerative connection and the selective network 35-31, the voltage developed across circuit 31 is relatively free of modulation components, and, therefore, is substantially voltage of double the I. F. carrier. This voltage is applied to the diode 26 along with the signal voltage appearing across circuit 28, and the two voltages are in the same or opposite phase. Here, again, it is required that the accentuated unmodulated second harmonic voltage be of relatively high magnitude with respect to the signal voltage developed across circuit 28. There is secured a selective improvement in detector efficiency in this second detector stage as disclosed in my aforesaid co-pending application. Detection takes place, and there is developed across resistor 29 audio voltage components as well as direct current voltage components. The audio frequency voltage is taken off by a slideable tap 36, and is then fed to one or more audio frequency amplifiers which may be followed by any desired type of reproducer.

The direct current voltage components are utilized for automatic volume control (AVC) action. This is accomplished by connecting the signal grids of regenerative amplifier tubes 14 and 32 to the AVC lead 37. The lead 37 may terminate in an adjustable tap 38 so as to provide an adjustment of gain control bias. Proper filter resistors 39 may be included in the AVC line so as to prevent pulsating voltage components from being applied to the grids of tubes

14 and 32. The AVC connection functions to control the regenerative amplifier tubes in a sense such as to maintain signal voltage across circuit 28 substantially uniform regardless of signal carrier amplitude variation at collector 1 over a wide range. The AVC arrangement, additionally, functions to reduce the gain of the regenerative amplifier tubes simultaneously with the reduction of the gain of tube 8 as the carrier amplitude increases. In this way there is maintained a fairly proportional relation between the signal voltage applied to each of the mixer and detector tubes and the accentuated carrier voltage.

It will now be seen that there has been provided at least two networks in cascade, each of which utilizes selective improvement in detector efficiency. The first of the stages functions to produce signal voltage of double the I. F. value, whereas the subsequent stage derives from the second harmonic signal voltage the desired modulation component voltage. There is thus secured an improvement in the over-all selectivity which is analogous to the increase in amplification obtained by two stages.

In Fig. 2 there is shown a modification of the system wherein there is employed two pair of push-pull, or balanced, mixer tubes in cascade. In other words, in place of the signal tube 8 employed in the I. F. mixer stage, there is utilized a pair of tubes 40 and 41 each of which may be of the same type as tube 8. The cathodes of the tubes 40 and 41 are connected in common to a properly by-passed grid bias resistor 42, while the plates of the two tubes are connected to the opposite sides of the second harmonic output circuit 24—23. The mid-point of coil 23 may be connected to a source of positive potential. The signal grids of tubes 40 and 41 are connected to the opposite sides of input circuit 7, while the third grids 43 and 44 of tubes 40 and 41 respectively are connected to the output circuit 45 of the regenerative amplifier tube 14. It will be noted that an additional tuned stage is interposed between grids 43, 44 and the plate circuit 20—19 of tube 14 in order to secure correct phase relation between the exalted carrier and the signals. Furthermore, the grid 17 of tube 14 is coupled to the primary circuit 6 by condenser 46. Otherwise, the regenerative amplifier stage is similar to that shown in Fig. 1 associated with tube 8. Here, again, the regenerative amplifier functions to accentuate the I. F. carrier while substantially removing all of the modulation voltage components. Hence, there is applied to grids 43 and 44 voltage of the I. F. value which has practically no modulation components. However, to the signal grids of tubes 40 and 41 there is applied in push-pull relation the normal I. F. signal voltage. In each of tubes 40 and 41 the voltages on the respective grids 43 and 44 are in like and unlike phases with the I. F. signal voltage on each of the signal grids.

There is developed in the output circuit 24—23, as in the case of Fig. 1, voltage of double the I. F. value. The detector input circuit 28 has the mid-point of its coil connected to ground, and the signal grids of the detector tubes 50 and 51 are connected to opposite sides of input circuit 28. The common cathode lead of the two tubes is connected to ground through a properly by-passed bias resistor 52. The input circuit 28 is, also, tuned to the second harmonic of the I. F. value. The plates of tubes 50 and 51 are con-

nected in push-pull relation. That is to say, they are connected to the opposite ends of the primary winding of audio transformer 53, and the mid-point of the primary winding is connected to a source of positive potential. Tubes 50 and 51 are otherwise arranged in a manner similar to the arrangement of tubes 40 and 41. In other words, the third grids of each of tubes 50 and 51 are connected to the output of a second regenerative amplifier stage.

The second regenerative amplifier stage comprises, as in the case of Fig. 1, the tube 32. The coupling condenser 34 connects the grid of tube 32 to the plate of tube 41. Hence, there is applied to the tube 32 signal voltage of the second harmonic of the I. F. Both the selective circuits 35 and 31 are tuned to the second harmonic frequency as in Fig. 1. As explained in the latter case, the regenerative amplifier strips the modulation component frequencies from the second harmonic carrier, and across circuit 31 there is developed voltage of substantially the I. F. second harmonic. This voltage is applied to the grids 60 and 61 of tubes 50 and 51 respectively. The voltages applied to grids 60 and 61 are in like and unlike phase with the signal voltages applied to the respective signal grids of the tubes. The accentuated double I. F. voltage is relatively high in magnitude with respect to the signal voltages applied to the signal grids. The tubes 50 and 51 act as a balanced detector, and audio modulation component voltage appears across the output transformer secondary winding.

The gain control is provided in this case by a separate diode 70, whose anode 71 is coupled to the high potential side of circuit 31 by coupling condenser 72. The load resistor 73 is connected between the anode 71 and the grounded diode cathode. The AVC connection is made from the load resistor 73 to the grids of each of the tubes 14 and 32, filter resistors 39 being employed to suppress pulsation voltage components. Slider 74 may be adjusted along resistor 73 to select a desired bias value.

In the modification of Fig. 3, the balanced tubes 50 and 51 are replaced by a pair of balanced diodes. The latter may be housed in a common tube 80, such as one of the 6H6 type. Thus, anode 81 is connected through condenser 82 to one side of input circuit 28, while anode 83 is coupled through condenser 84 to the opposite side of circuit 28. The accentuated second harmonic I. F. voltage is injected into the detector network by connecting the high potential side of circuit 31 to the mid-point of the coil of input circuit 28. The AVC connection 37 is made to the mid-tap on load resistor 90 connected between anodes 81 and 83.

The cathodes of the diodes are connected to the grounded mid-tap of resistor 91. The second harmonic by-pass condenser 92 shunts one half of resistor 91, while by-pass condenser 93 shunts the other half. The audio voltages at the opposite ends of resistor 91 are applied in push-pull relation to the signal grids of the twin-triode tube 100. The audio output transformer 101, having its primary winding in push-pull connection with the plates of tube 100, feeds the audio voltage to following stages. There is had full wave rectification of the applied fully modulated second harmonic voltage and accentuated second harmonic voltage. The rectification in each half of the network is similar in action to that had with the network in Fig. 1. Resistor 90

supplies the AVC bias, and also acts as a filter resistance.

While I have indicated and described several systems for carrying my invention into effect, it will be apparent to one skilled in the art that my invention is by no means limited to the particular organizations shown and described, but that many modifications may be made without departing from the scope of my invention, as set forth in the appended claims.

What I claim is:

1. In a system for receiving modulated carrier energy, the method which includes reducing the energy to a lower carrier frequency, producing unmodulated energy of said reduced carrier frequency, heterodyning the modulated carrier energy of reduced frequency with said unmodulated energy of said reduced carrier frequency, deriving from the combined energies modulated carrier energy of an harmonic of said reduced frequency, producing unmodulated energy of said harmonic frequency, combining said modulated harmonic energy with said unmodulated energy of said harmonic frequency to produce energy of the modulation component frequencies.

2. In a system for receiving modulated carrier energy, the method which includes reducing the energy to a lower carrier frequency, producing unmodulated energy of said reduced carrier frequency, heterodyning the modulated carrier energy of reduced frequency with said unmodulated energy of said reduced carrier frequency, deriving from the combined energies modulated carrier energy of an harmonic of said reduced frequency, deriving unmodulated energy of said harmonic frequency from said modulated harmonic energy, combining said modulated harmonic energy with said unmodulated energy of said harmonic frequency, and rectifying the last named combined energies thereby to produce energy of the modulation component frequencies.

3. In a system for receiving modulated carrier energy, the method which includes reducing the energy to a lower carrier frequency, producing unmodulated energy of said reduced carrier frequency, heterodyning the modulated carrier energy of reduced frequency with said unmodulated energy of said reduced carrier frequency, deriving from the combined energies modulated carrier energy of an harmonic of said reduced frequency which is double said carrier frequency, removing substantially all the modulation from a portion of said modulated double harmonic energy thereby to provide unmodulated double harmonic carrier energy, combining said modulated harmonic energy with said unmodulated energy of said double harmonic frequency to produce energy of the modulation component frequencies.

4. In a system for receiving modulated carrier energy, the method which includes reducing the energy to a lower carrier frequency, stripping the modulation from a portion of the modulated reduced carrier energy to provide unmodulated reduced carrier energy, heterodyning the modulated carrier energy of reduced frequency with said unmodulated energy of said reduced frequency, deriving from the combined energies modulated carrier energy of an harmonic of said reduced frequency, producing unmodulated energy of said harmonic frequency, combining said harmonic energy with said unmodulated energy of said harmonic frequency to produce energy of the modulation component frequencies, and varying the magnitudes of said unmodulated ener-

gies in response to amplitude variations in said carrier energy.

5. In an audio-modulated carrier voltage receiving system, the method which includes converting collected carrier voltage to modulated carrier voltage of intermediate frequency, deriving substantially unmodulated carrier voltage of said intermediate frequency from said modulated intermediate frequency voltage, combining said modulated intermediate frequency voltage with said substantially unmodulated voltage of said intermediate frequency, deriving from the combined voltages modulated carrier voltage of a frequency which is a multiple of said intermediate frequency, deriving from said modulated multiple frequency every substantially unmodulated voltage of said multiple frequency, combining said modulated multiple frequency carrier voltage with said substantially unmodulated voltage of said multiple frequency thereby to produce voltage of audio frequencies.

6. In an audio-modulated carrier voltage receiving system, the method which includes converting collected carrier voltage to modulated carrier voltage of intermediate frequency, producing substantially unmodulated voltage of intermediate frequency, combining said modulated intermediate frequency voltage with said substantially unmodulated voltage of said intermediate frequency, deriving from the combined voltages modulated carrier voltage of a frequency which is a second multiple of said intermediate frequency, producing substantially unmodulated voltage of said multiple frequency, combining said modulated multiple frequency carrier voltage with substantially unmodulated voltage of said multiple frequency thereby to produce voltage of audio frequencies and varying the magnitude of said unmodulated voltages in accordance with variations in the amplitude of said carrier.

7. In a modulated carrier energy receiver system, producing unmodulated energy of a predetermined carrier frequency, mixing modulated carrier energy of said predetermined carrier frequency with said unmodulated carrier energy of the same frequency thereby to produce modulated carrier energy of at least double said carrier frequency, removing from a portion of said modulated double carrier frequency energy substantially all modulation, mixing said double frequency modulated energy with said unmodulated carrier energy of said double frequency, and deriving from the last mixed energies voltage of the modulation component frequencies.

8. In a modulated carrier energy receiver system, producing unmodulated energy of a predetermined carrier frequency, mixing modulated carrier energy of said predetermined carrier frequency with said unmodulated carrier energy of the same frequency in phase opposition thereby to produce modulated carrier energy of at least double said carrier frequency, removing from a portion of said modulated double carrier frequency energy substantially all modulation, mixing said double frequency modulated energy with said unmodulated carrier energy of said double frequency in phase opposition, and deriving from the last mixed energies voltage of the modulation component frequencies.

9. In a modulated carrier energy receiver, means for reducing said energy to a lower carrier frequency, means deriving substantially unmodulated carrier energy of said reduced frequency from said modulated energy of reduced frequency, means mixing said latter modulated

energy with said unmodulated energy in phase opposition to produce modulated carrier energy of the second harmonic of said reduced frequency, means deriving substantially unmodulated carrier energy of said second harmonic frequency from said second harmonic modulated energy, and means for rectifying combined second harmonic modulated and unmodulated energies to produce voltage of modulation component frequencies.

10. In a modulated carrier energy receiver, means for reducing said energy to a lower carrier frequency, means deriving substantially unmodulated carrier energy of said reduced frequency from said modulated energy of reduced frequency, means mixing said latter modulated energy with said unmodulated energy in phase opposition to produce modulated carrier energy of the second harmonic of said reduced frequency, means deriving substantially unmodulated carrier energy of said second harmonic frequency from said second harmonic modulated energy,

and full wave rectification means for rectifying combined second harmonic modulated and unmodulated energies to produce voltage of modulation component frequencies.

- 5 11. In a modulated carrier energy receiver, means for reducing said energy to a lower carrier frequency, means deriving substantially unmodulated carrier energy of said reduced frequency from said modulated energy of reduced frequency, means mixing said latter modulated energy with said unmodulated energy in phase opposition to produce modulated carrier energy of the second harmonic of said reduced frequency, means deriving substantially unmodulated carrier energy of said second harmonic frequency from said second harmonic modulated energy, and means for rectifying combined second harmonic modulated and unmodulated energies in phase opposition to produce voltage of modulation component frequencies.
